UNITED STATES PATENT OFFICE.

JOHN DANIEL, OF MILWAUKEE, WISCONSIN, ASSIGNOR, BY MESNE ASSIGNMENTS, TO KOEHRING COMPANY, OF MILWAUKEE, WISCONSIN, A CORPORATION OF WISCONSIN.

CHUTE-OPERATING MEANS.

Application filed December 23, 1919. Serial No. 346,907.

To all whom it may concern:

Be it known that I, JOHN DANIEL, a citizen of the United States, residing at Milwaukee, in the county of Milwaukee and State of Wisconsin, have invented certain new and useful Improvements in Chute-Operating Means, of which the following is a specification.

Certain engineering undertakings of the present day are attended with remarkable and unusual requirements in concrete mixing. As an instance, the rapid laying of concrete roads has progressed to the point where as much as seventy linear feet of sixteen-foot pavement have been put down per hour, and indeed a maximum of one hundred twenty six feet has been reached on certain work.

Obviously, operations like the foregoing necessitate the mixing of concrete in huge batches as large for instance as fifty five cubic feet, and the rapid discharging of said batches from the mixing plant.

With the foregoing in view, the present invention comprises improved means whereby the discharging device of extremely large concrete mixers may be operated by power, and operated with speed as well.

In the carrying out of the invention, I contemplate broadly certain provisions whereby the motion transmitted to the mixing drum of the mixer may be employed, for imparting movement to the discharge chute of the mixing machine, whereby to throw the said chute into a position for discharging action and to position the same inoperative to perform its discharge function.

This invention involves improvements in the type of concrete mixing machine illustrated by Koehring Patents Nos. 899,414 of September 22, 1908, and 1,126,487 of January 26, 1915, wherein the discharge chute employed operates as a mixing element of the machine, owing to its function of intercepting and returning toward the receiving end of the drum the concrete aggregates in process of mixing or agitation.

In machines of this type a very considerable load is constantly received upon the discharge chute as it assists in mixing, and therefore the power means used according to this invention is especially advantageous when employed in connection with discharging devices of this kind, though its utility,

of course, is not limited to any particular type of discharging means for mixers. In matter of fact, the means of the invention might be used advantageously for operating any associated moving part of the mixer where the manual operation is unusually burdensome. 60

In the accompanying drawings which are to be studied in connection with the following specific description of the improvements hereof;

Figure 1 is a front elevation showing more particularly the mixing drum of a concrete mixer, equipped with the means comprising the invention, in a preferred 70 form.

Figure 2 is a vertical sectional view of the same.

Figure 3 is a view and side elevation of the trip member. 75

Figure 4 is an edge view of the trip member.

Figure 5 is a view showing a modified form of the invention wherein an inclined cam means is employed as the actuating 80 element for the trip.

Figure 6 is a detail view showing more clearly the cam device of Figure 5.

Figure 7 is a side view of the trip used in the construction of Figure 5. 85

To those versed in the art the operation of the customary rotating drum A of concrete mixing means at present commonly used is obvious, the aggregates being received in the drum and subjected to agitation by devices of the latter in the well known manner. The discharge chute for the drum or mixing machine A is designated B and is pivotally mounted at 1 upon a stationary guard or splash plate so as to incline inwardly into the drum to act as a mixing element, in which position it is inoperative for discharge purposes. The inwardly inclined position is illustrated by dotted lines, whilst in full lines the chute B is shown in its discharging position. The chute B may be operated manually by means of a lever 2 extending from the shaft 3 supported on the frame work 10 which shaft 3 is connected by an arm 4 and link 5 with the chute B. 95 Obviously, the rocking of the arm 4 outwards will shift the chute B into the dotted line position of Figure 2, from its full line position. The manual lever 2 will not ordinarily be used for the operation of the 100

105

110

chute B, though of utility in emergencies and for the restoration of the chute to its normal position inactive for discharging purposes.

5 The power actuating means for the chute is comprised of trips 6 which are splined upon the shaft 3 and are shiftable in opposite directions by means of a hand rod 7 connected with the upper ends of spaced bars 8, one of which is located at each side of the chute B and suitably pivoted at 9 on the frame work 10 of the machine, the latter carrying the part to which the chute B is pivoted. The trips 6 comprise members adapted to slide on the shaft 3 under the influence of actuation of the parts 7 and 8, whereby either one of said trips may be brought into the path of actuating means on the drum A, said means according to one 10 construction comprising rollers 11 suitably journaled upon brackets 12 which are secured in any substantial way to the flanged ring 13 which forms a part of the mixing drum unit. Each trip 6 embodies a series 15 of arms 6^a which actually engage the rollers 11 or actuating elements on the drum.

It will be apparent that the movement of the trips 6 in one direction will interpose one of them in the path of movement of the 20 rollers 11 and these rollers will in progressive order engage the projections or arms 6^a and thereby cause actuation of the shaft 3 so as to throw the chute B from an inoperative position for discharging, into its discharging position. A movement of the trips in an opposite direction will carry the other trips into the path of movement of the rollers 11 thus causing a shifting or movement of the chute B from its discharging 25 position into non-discharging position. Under the conditions the load of operation of the chute B may by the aforesaid mechanism be placed upon the drum itself, and the latter being power driven no difficulty will 30 be experienced in securing the desired operation of said chute. This is true irrespective of the quantity of materials of the aggregate being mixed falling upon the chute B, if the latter is of the type constituting a mixing 35 element.

In Figures 5, 6 and 7, there is shown a somewhat circular cam actuating element 14 affixed to the ring 13 of the drum A and adapted to engage a trip 15 in the form of 40 an arm mounted on the shaft 3. A hand lever 16 on a shaft 17 is adapted to operate the yoke 18 which engages the grooved head 15^a of the trip 15, whereby to shift the trip 15 into a position wherein its roller 15^b will 45 engage the cam element 14. The latter during the turning of the drum A will rock the arm 15 and cause rocking of the shaft 3 sufficiently to move the chute connected therewith, to a discharging position. The 50 turning of the chute to a non-discharging

position may be accomplished by hand, or if desired by a movement of the arm 15 into cooperation with a cam element like that designated 14, but which is disposed reverse thereto.

Obviously, various modifications in the detail features including the actuating elements on the drum, and the trip means connected with the shaft by which the discharging chute or a like associated device is operated, may be employed so long as the general principle of transmitting movement from one part to another is utilized.

Having thus described my invention what I claim as new is:

1. In combination a rotary mixer, a normally stationary chute coacting therewith, an actuating element for said chute on the mixer, trip means for moving the chute from one position to another, and means for 85 adjusting at will the trip means and said element relatively to each other so as to cause operation of the chute.

2. In combination a mixing machine comprising a rotative drum, a movable chute associated with said drum, means for supporting the chute adjacent to the drum, said chute being adapted to discharge the contents of the drum, and means for effecting movement of the chute by the drum.

3. In combination, a mixing machine, comprising a rotative drum, a movable chute supported independently of said drum, adapted for discharging the same and for cooperating with the contents of the drum for mixing purposes, and means for causing movement of said chute into discharging or mixing positions, operated from the drum.

4. In a mixing machine, a power operated agitating device, a discharging means therefor, a trip connected with the discharging means and normally inactive, and means on the agitating device to engage said trip for actuating the discharging means, and means to adjust the last means and trip relatively to one another for coaction as aforesaid.

5. A mixing machine, comprising a power operated agitating device, a chute mounted for co-operation with the agitating device, an actuating element for the said chute on the agitating device, a trip means connected with the chute, and means to move said trip means into cooperation with the actuating element at will for operating the chute by the agitating device.

6. Means as claimed in claim 5 in which the actuating element is a means projecting from the agitating device, and the trip means comprises a manually operable member movable into and out of the path of movement of said actuating element.

7. In a mixing machine, in combination, a mixing drum of the power operated type, a reversible chute, adjustable to occupy discharging and non-discharging positions de-

pendent on the position of the reversal, and coacting with the drum for discharging it, and means intermediate the drum and chute whereby to reversibly operate the chute by the drum.

8. In a mixing machine, in combination, a mixing drum of the power operated type, a reversibly operating chute coacting with said drum for discharging purposes, said chute adjustable to occupy discharging and non-discharging positions dependent on the direction of reversal, and means intermediate the drum and chute whereby to operate the chute from the drum, comprising a trip and actuating element, the trip being movable into and out of the path of the actuating element.

9. In a mixing machine, in combination, a mixing drum of the power operated type, a reversibly operable chute coacting with said drum for discharge purposes, means intermediate the drum and chute whereby to operate the chute from the drum, comprising an actuating element on the drum, and trip means for the chute at opposite sides of the axis of the drum, cooperative with said actuating element, with means to render either trip means active in relation to the actuating element.

10. In a mixing machine, a combination of a rotary mixing drum, a chute cooperating with said drum and means to operate the chute from the drum consisting of trip means on one of said parts and an actuating element on the other, and anti-friction means intermediate the two, with means to at will place the trip means and actuating element in and out of cooperation.

11. In combination, a mixing drum, a chute to cooperate with the contents of the drum substantially as described, and means to operate the chute from the drum consisting of a shaft, a movable trip on the shaft, means projecting from the drum to engage said trip to operate the latter, and connections between the shaft and the chute to cause movement of the chute when the shaft is operated on actuation of the trip and means to move the trip into and out of cooperation respecting the parts on the drum cooperative therewith.

12. In combination, a mixing drum adapted for rotation, a chute for cooperation with the contents of said drum, a shaft connected with said chute to move the same, an actuating member on the drum, a trip on the shaft movable into and out of cooperation with the actuating member on the drum for shifting the chute in one direction, a second trip on the shaft cooperative with the actuating member on the drum for shifting the chute in another direction, and operating means to move the trips aforesaid for the actions above stated.

13. In combination, a rotating mixer, an actuating projection thereon, a discharge chute cooperative therewith to discharge its contents, a shaft to operate said chute and a trip movable on the said shaft into and out of cooperation with the actuating part of the drum so that the movement of the drum may be imparted to the shaft substantially as set forth.

In testimony whereof I affix my signature.

JOHN DANIEL.
